UNITED STATES PATENT OFFICE

104,382

DESIGN FOR AN AUTOMOBILE ANTENNA

Robert P. Schiffmann, Chicago, Ill.

Application March 17, 1937, Serial No. 68,237

Term of patent 7 years

To all whom it may concern:

Be it known that I, Robert P. Schiffmann, a citizen of the United States of America and a resident of Chicago, Cook County, Illinois, have invented a new, original, and ornamental Design for an Automobile Antenna, of which the following is a specification, reference being had to the accompanying drawing, forming a part thereof.

I claim:

The ornamental design for an automobile antenna substantially as shown.

ROBERT P. SCHIFFMANN.
